UNITED STATES PATENT OFFICE.

JOHN EDWIN DENNIS, OF LONDON, ONTARIO, CANADA.

METAL-WINDOW CONSTRUCTION.

Application filed July 19, 1926. Serial No. 123,448.

The principal objects of this invention are to greatly simplify the construction of the frame and sash of a sliding metal window structure, reducing the cost of construction and providing a structure which may be made very strong and durable.

A further object is to devise a structure in which an extraordinary contacting sealing surface is provided which will prevent 10 draught.

A still further object is to obtain the maximum of area of light openings for the given area of opening in the wall.

The principal feature of the invention consists in the novel construction and arrangement of the box frame and the sash whereby a pair of right angularly arranged flanges on the sash structure engage in sliding contact with surfaces of the box frame and the box 20 frame is formed with a single inside facing strip formed with longitudinal parallel spaced ribs presenting outwardly opening channels and the remaining portion of the box is formed of a single moulded sheet.

25 In the drawings, Figure 1 is a vertical mid-sectional view through a pair of sash and the sill and lintel of a window frame constructed in accordance with this invention.

Figure 2 is a perspective cross sectional 30 view through the frame, cut through both upper and lower sash members.

In the construction herein shown, the window frame 1 is formed of a substantially rectangular cross-sectional shape of a single 35 sheet of metal having the inside edge strips 2 and 3 turned inwardly at right angles to the inner and outer edges 4 and 5 of the frame.

40 Arranged inside of the strips 2 and 3 is a single sheet 6 which is shaped with a pair of rectangular shaped ribs 7 and 8 forming grooves which open outwardly to the inner side of the window frame. These grooves are partly overlapped by the inward edges of the strips 2 and 3 leaving a space in the form 45 of a longitudinal slot 9 close to the inward side of each of the ribs.

The sash are formed of a very simple structure made of a T-bar 10, the web 11 of which fits in sliding contact against the outer face 50 of the sheet 6 of the frame on the upper sash and on the lower sash this web engages the face of the flange 2 to the outward side of the rib 7. A very wide surface contact is thus provided which very effectively prevents 55 the inflow of air.

One of the flanges 12 of the T head of the

sash structure projects through the slot 9 into the grooves formed by the ribs 7 and 8 and at least one of the faces of the flange 12 engages one of the faces of the longitudinal rib 60 formed in the sheet 6. This face is arranged in right angular relation to the face of the web 11 engaging the casing wall and a very secure wind-tight seal is made.

It will be readily seen that the construction of the frame is the very simplest possible form, in that there are nothing but plain right angular bends in a single sheet of material. Likewise, the inner sheet 6 is simply formed up with the longitudinal ribs 7 and 8 therein all formed with right angular bends. The two sheets are then slipped together and secured by means of spot welding, screws or rivets along the flanged portions 75 2 and 3.

The lintel 13 is formed in a similar manner to the side stiles of the frame, except that the inner strip 14 has but a single groove to receive the flange of the top sash. The sill 15 is preferably provided with a double offset 80 forming a shoulder 16 to engage the flange of the sash frame and a shoulder 17 to engage the inner edge of the web.

The meeting rails of the window sash may be formed in any desirable manner, but they 85 are here shown with the upper sash constructed with a horizontal groove 18 into which a flange 19 turned downwardly from the top bar of the lower sash enters. A thoroughly weather tight joint is thus provided. 90

It will be readily understood that window construction such as described is extremely simple to make, will cost very little and the contact surfaces are so arranged that a very excellent weather-proof structure is produced.

What I claim as my invention is:

1. A metal window, comprising a box frame formed of a single sheet of metal shaped into rectangular form and having inwardly turned free edges spaced apart, a separate sheet of metal secured inside and bridging the space between the free inturned edges of the frame and having a pair of longitudinal ribs with parallel and rectangularly arranged sides parallelly spaced therein, the free spaced edges of the frame overlapping a portion of the channels formed by said ribs leaving longitudinal slots, and sash members formed of T bars, the webs of which are slidably engage the face of the box frame in flat contact and the outer flanges of which

extend into the slots formed by the channels in said separate sheet and the overlapping free edges of the box structure, the flanges of the T bars having their faces right angularly arranged in relation to the webs engaging a longitudinal face of the channels formed in the single sheet.

2. A metal window comprising a frame formed of a single sheet of metal shaped into a rectangular box-like form having the free edge portions flanged into a common plane with the edges thereof spaced apart, a separate sheet of metal extending across the open side of said box frame and engaging the flat

inner faces of the free edge portions in rigid sealing contact, said latter sheet being formed with longitudinal rectangular shaped channels opening toward the sash opposite the edges of said flanged edge portions, and sash formed of T-bars having their web portions slidably engaging the outer side of said flanged edge portions of the box frame and their head flanges extending past the free edges of the box flanges into said channels and having one side slidably engaging the flat channel wall.

JOHN E. DENNIS.
